SCARF

Sam B. Preston, Birmingham, Ala.

Application November 9, 1936, Serial No. 109,942

5 Claims. (Cl. 2—91)

My invention relates to a novel and distinctive type of muffler or scarf which is characterized by the provision of a neck band adapted to be clasped about the wearer's neck and formed or faced with the scarf material, the scarf being of the wide flowing type and having its upper end gathered and sewn to the neck band so as to drape from the top edge thereof in a manner to simulate a muffler or hand tied scarf that has been arranged effectively to cover and protect the wearer's collar and chest.

The chief object of my invention is to obtain with a very small amount of material all of the advantages of the present long muffler scarfs as worn by men generally for the protection of their collars and for added warmth in winter.

My invention further contemplates so designing and adapting the scarf that it is available for summer wear in place of a collar and is adapted, when so worn with a jacket or coat, to enable the wearing of a shirt to be dispensed with.

The distinguishing feature of my invention lies in the provision of a relatively short worn scarf end having a length sufficient to be caught under the coat lapels and having a width sufficient to completely cover the front of the collar and neck opening of the coat or overcoat, like a muffler. This wide short scarf end is gathered at its upper end and preferably sewn into the top seam of the neck band so as to fall with draped plaited effect thereover and straight down. For many purposes it will be desirable to stiffen the neck band, particularly where worn without a collar, to hold the scarf up closely under the chin.

The objects and advantages of my improved type of scarf will be better understood by the following detailed description and the appended claims, reference being had to the accompanying drawing which illustrates my invention in its preferred embodiment only, and in which:

Fig. 1 is a front view showing my improved scarf in service as a muffler with the neck band clasps applied for fastening from the right hand side.

Fig. 2 is a detail view of the scarf elements comprising the scarf proper and the neck band, the latter being shown in opened-out position with its inside face uppermost and broken away to show the preferred manner of stitching the plaited scarf and stiffening element inside the neck band and showing the clasps applied reversely to the showing in Fig. 1 for fastening from the left hand side.

Fig. 3 is a view corresponding to Fig. 2, showing the neck band inverted and the plaited scarf

draping over its upper edge and thus presenting the scarf with its parts in the position of use as viewed in front elevation.

Fig. 4 is a diagrammatic view illustrating the relation of the stitched elements as shown in an end view of Fig. 3 looking to the left.

Similar reference numerals refer to similar parts throughout the drawing.

In the embodiment of my invention illustrated, I take a relatively wide strip of fabric, either woven or knitted and single or double ply according to the fabric which should be of any character suitable for use in men's scarfs or mufflers. These scarfs at the present time are generally about four feet in length so that they may be passed around the neck and then either tied or draped so as to protect the neck opening with their free ends caught and held in place under the coat or overcoat. This requires a substantial amount of material which is generally expensive, and the scarf as a whole is somewhat bulky and too large to be conveniently carried in the pocket of the overcoat, when not being worn.

My improved muffler scarf comprises a relatively short strip of suitable scarf fabric indicated at 5 which has a length sufficient to extend from the collar top of the wearer to a point below the first button level of the coat or overcoat. Therefore, it need not be more than 12" to 18" in length and requires only a minor fraction of the material ordinarily used to make a scarf.

The neck band element of my scarf is preferably formed of a narrow strip of the same scarf material and, if it is made straight, as is permissible, it may be formed by folding this strip upon itself to form the inner and outer plies 6 and 7, respectively, of the neck band. These plies are sewn together at one edge which as worn becomes the upper edge with a suitable seam 8, but before this seam is completed one end of the scarf section 5 is gathered in plaits and sewn in place so when the neck band is inverted, it will fall in plaits over what then is the top of the neck band. Preferably, the plaited end of the scarf is inserted between the neck band plies and is secured by the same seam 8 which closes the top of the neck band.

The neck band has attached to its front outer face in position to be overhung by the scarf, one or more snap fastener elements 9, and the free end of the neck band is provided on its inner side with complementary clasp members 10. It is contemplated that sufficient of these clasp members will be provided so that the neck band can be adjusted to fit the neck size of the wearer, the

number used being immaterial since they will be concealed by the scarf. Also the neck band can be attached so as to be fastened from either side desired, or in any suitable way, the form shown 5 in Fig. 1 having the neck band projecting to the right, instead of to the left, of the scarf, as shown in Figs. 2 and 3, and therefore adapted to be fastened from the right, whereas the scarf of Fig. 2 must be fastened from the left.

10 Where it is desired to stiffen the neck band so that the scarf will be held up better at the throat, a stiffening strip 11 is inserted in the neck band and held in place by the stitching 8, or otherwise. This strip as well as the neck band 15 may be appropriately shaped to conform to the throat of the wearer and if desired the strip may be coextensive with the gathered end of the scarf, though a shorter stiffening piece may serve all needed purposes.

20 While I prefer the manner of attachment of scarf to neck band above described, it will be understood that the scarf may be used without the stiffener strip and may be attached to the neck band in any manner so that in use it will 25 fall in plaits from the top of the neck band as worn.

Having manufactured the scarf in the manner described, the wearer applies it by turning the neck band under from the position of Fig. 2 until 30 it is inverted and folded against the back side of the scarf, as in Fig. 3, and then drawing the neck band around the throat, either from the right or left according to the position of attachment thereto of the scarf with the center of the 35 scarf held in line with the center of the opening between the coat lapels 12. The free end of the neck band is passed under the scarf and its fastener element or elements 10 are interlocked with the appropriate complementary clasp element or elements 9 on the neck band under the 40 scarf, and when the neck band has thus been fastened at the front, the scarf will drape itself gracefully and naturally as it falls in plaits over the neck band and may be gathered in under 45 the lapels 12, giving a pleasing and attractive, tied muffler appearance to the scarf as thus worn.

The article will be light, short, comparatively 50 inexpensive, will serve every purpose of the present standard mufflers for winter use, and will form a soft attractive scarf, for use with or without shirts, for summer wear. The scarfs for the latter purpose can be made of light or white material which will be soft and drape gracefully 55 and attractively, and the width of the scarf is such that the absence of any shirt being worn under the coat will not be observed.

While I have shown my invention in but two 60 forms, it will be obvious to those skilled in the art that it is not so limited, but is susceptible of

various other changes and modifications, without departing from the spirit thereof, and I desire, therefore, that only such limitations shall be placed thereupon as are imposed by the prior art or as are specifically set forth in the appended 5 claims.

What I claim is:

1. A muffler scarf of the character described, comprising a strip of suitable scarf material having sufficient width after plaiting substantially to cover the front of the neck and the opening between the wearer's coat lapels, in combination with a neck band, the upper end of the scarf strip being gathered and attached along the upper edge of the neck band in position as 10 the neck band is worn to fall in gathered folds from the top outside edge of the neck band, and means along the upper edge of the neck band concealed by the depending scarf strip to fasten the neck band in position around the neck. 20

2. A muffler scarf of the character described, comprising a strip of suitable scarf material having sufficient width substantially to cover the front of the neck and the opening between the wearer's coat lapels, in combination with a neck 25 band, the upper end of the scarf strip being gathered and attached to one end portion of the neck band along its upper edge in position as worn to fall in gathered folds over, and conceal the front of, the neck band, fastening elements 30 on the outside of one end of the band along the upper edge and concealed by the depending scarf strip, and complementary fasteners on the inner upper edge of the neck band.

3. In a muffler scarf, in combination with 35 a neck band, a scarf portion attached to and depending from the upper edge of the neck band, and gathered where it joins the band, fastening elements on the outer layer of the neck band under the scarf, and complementary fastening elements 40 on the free end of the neck band, thereby to bring the neck band lap in concealed position under the scarf. 40

4. A muffler scarf according to claim 3, in which a suitable stiffener element is interposed 45 in the front portion of the neck band and held by the fastening for the gathered end of the scarf portion to support said scarf portion at the front.

5. A muffler scarf comprising a neck band portion, spaced fastening elements on the upper outer edge of one end of the band portion complementary fastening elements on the upper inner edge of the band portion, and a scarf portion secured to and depending from the upper 55 edge of the band portion, said scarf portion being gathered at the point of attachment and concealing the fastening elements. 50
